UNITED STATES PATENT OFFICE.

HENRY CLAY WADE, OF LOS ANGELES, CALIFORNIA.

METHOD OF PRODUCING MOTOR FUEL.

Application filed August 7, 1922. Serial No. 580,092.

To all whom it may concern:

Be it known that I, HENRY CLAY WADE, a citizen of the United States, residing in Los Angeles, county of Los Angeles, and

5 State of California, have invented certain new and useful Improvements in Methods of Producing Motor Fuel, of which the following is a specification.

The present invention relates more particularly to a method of treating light hydrocarbon gases such as natural gas and casing head gas. A further object is the production of motor fuel by combining the recovered light hydrocarbon liquid with heavier hydrocarbon bodies simultaneously with the recovery of said liquid from the gas. In other words the production of motor fuel is, in one aspect of the invention, a direct result from the gas liquefying process. The 10 partial recovery of condensable hydrocarbons from natural gas has been heretofore accomplished by compression methods, and also by permitting the gas to pass through pools of crude or refined petroleum oil, the 15 latter method effecting absorption of the readily condensable portion of the liquid content of the gas. By means of the present invention a very much greater recovery is obtained from such gas. My method also is 20 applicable to coke oven gases and normally non-condensable gases from petroleum-oil cracking plants.

In describing my method I will refer to the accompanying drawing, in which—

25 Fig. 1 is a diagrammatic elevation of the apparatus, and

Fig. 2 is a sectional detail view of the injector intermediate the coil intake and the gas, oil and water lines.

30 By reference to the drawing it will be seen that the apparatus consists of an oil tank 1, oil line 1^x, a water tank 2, water line 2^x, a furnace 3, a gas line 4, a coil 5 within the furnace, and other instrumentalities now to be described. By reference to Fig. 2 it will be seen that the outlets of the gas, oil and water lines communicate with an atomizer or injector 6 having its discharge end within the intake of the coil 5. The outlet α of the 35 water line projects within and axially of the gas line at its outlet end; and in practice I have found that the proportionate diameters may be as follows. Assuming the diameter of the coil to be 2", the injector may be 1 $\frac{1}{4}$ ", the gas outlet end $\frac{1}{2}$ " and the water outlet end $\frac{1}{4}$ ". The tubes of the water and oil line

may be of any suitable diameter, as for example 3/4".

As a member of the water line, and suitably located within the furnace 3 is a water- 60 superheater coil 2^{xx}, and intermediate the latter and the water line outlet α is a pressure regulating valve 7. In practice I prefer to bring the water up to at least 212° F. in the superheater and to confine the super- 65 heated water so that it is not permitted to vaporize until it passes into the injector simultaneously with the oil and gas. This may be accomplished by feeding the water to the superheater under pressure and by 70 means of the pressure regulating valve 7 and the reduction in diameter of the outlet end of the water tube within this injector. The result is that the commingled oil and gas passing into the coil 5 (the upper turns of 75 which may be regarded as an expansion chamber) is subjected to the explosive action of water suddenly converted into steam. The mechanical effect is that the hydrocarbon bodies are broken up into exceedingly 80 fine particles thoroughly associated with the aqueous vapor particles, so that chemical reaction produced by heat and catalysis, as hereinafter explained, is rendered with maximum completeness, and as the lighter 85 constituents of the oil are broken up they are immediately "absorbed" by the aqueous vapor and are thus prevented from depositing free carbon.

It will be seen that the heating coil 5 90 leads to a suitable condenser 8, the latter discharging into a collecting tank 9, provided with a gas draw off tube 10, as customary.

Within the heating coil 5 preferably at 95 its outlet end is a catalyzer in attenuated mesh form, so as to present a large surface area in proportion to its mass.

In the operation of my method, a suitable temperature is produced within the furnace 100 or kiln 3 say 1100° F. and pressure regulating valves 11 and 12 are opened to permit the flow of oil and gas to the injector 6, the oil being under pressure, as from air conduit 13. If desired, the oil may be preliminarily heated. The water within super- 105 heater 2^{xx} rapidly reaches the steaming point, but being confined, as aforesaid, is not permitted to vaporize until it passes within the outlet end of the injector and in- 110 let of the heating coil, where, in the presence of the oil and gas, it suddenly bursts into

steam and thoroughly disseminates and associates the particles of oil and gas with its own particles of aqueous vapor. The vapors thence pass through the turns of the 5 heating coil, which may be of 150 ft. in length and 1", 2" or 3" in diameter. I have found that in my method low grades of fuel oil may be used, for example a crude petroleum oil from which kerosene and the 10 lighter constituents have been removed, as also the lubricants and asphalt, leaving a body of about 27 gravity. The breaking up of the oil by the explosive action of the steam and the intimate association of the oil particles with the particles of gas in the presence 15 of the aqueous vapor and heat may explain the very high "absorption," or recovery, of liquid hydrocarbon from the gas in the practice of my method, whereby I 20 have increased the recovery over compression methods by 2 gallons per 1000 ft. of casing head gas and have obtained corresponding increases in the use of less rich gas. The aqueous vapor reaching the catalyzer 25 C is partially disassociated thereby into its constituents of hydrogen and oxygen. Also, by means of a catalyzer formed in attenuated mesh and presenting a very large surface in proportion to its mass, I am able 30 to maintain at the point of final treatment of the vapors a temperature much higher than that within the coil in advance of the catalyzer. The catalyzer C not only disassociates the constituents of the steam, but 35 it effects new combinations between the thus

freed hydrogen, and the carbon and hydrogen atoms from the treated oil and gas, my condensed product being a new and stable motor fuel of superior quality.

In the production of my motor fuel I 40 have found that to 1000 cub. ft. of natural or casing head gas water may be employed to form steam to the extent of 50 per cent of the gas in volume, and fuel oil fifteen per cent in quantity. In such case the temperature 45 within the furnace may be 900° F. to 1400° F. The temperature within the coil from 650° F. to 1100° F. and the temperature after passing the catalyzer from 300° F. to 850° F. 50

Having described my invention what I claim and desire to secure by Letters Patent is—

The method of producing motor fuel, which consists in subjecting water to heat 55 while confined against vaporization until the water reaches a temperature of at least 212° F., passing the water into a body of commingled oil and gas so that said body is subjected to the explosive action of water 60 suddenly converted into steam, and subjecting the resulted mixture to heat and subsequent condensation.

In testimony whereof, I have signed my name to this specification in the presence of 65 two subscribing witnesses.

HENRY CLAY WADE.
